HANDLE FOR SNOW SHOVELS OR THE LIKE

Morton I. Thomas, R.D. 2, Box 182-H, Monroe, N.Y.

Filed July 11, 1962, Ser. No. 70,880

Term of patent 3½ years

(Cl. D39—1)

FIG. 1 is a front elevational view of a handle for snow shovels or the like, showing my new design;

FIG. 2 is a top plan view thereof; and

FIG. 3 is a side elevational view thereof.

The broken line showing of the shaft and blade members in FIG. 1 is for illustrative purposes only.

I claim:

The ornamental design for a handle for snow shovels or the like, substantially as shown and described.
